Inventor

UNITED STATES PATENT OFFICE.

JEAN-BAPTISTE BOUCHARD, OF INDIAN ORCHARD, MASSACHUSETTS.

GAME.

Application filed March 27, 1928. Serial No. 265,147.

This invention relates to games and has for an important object thereof the provision of game apparatus requiring skill in operation and of such character that it will 5 be relatively amusing.

A further object of the invention is the provision of game apparatus including a rotatable element divided into value fields and a stationary index for coaction with this 10 field together with a novel and improved means for causing rotation of the rotatable element which is both amusing and subject to skillful manipulation.

A still further and more specific object 15 of the invention is to provide in a game of this character apparatus for throwing a projectile against the rotatable element in such fashion as to cause rotation thereof.

These and other objects I attain by the 20 construction shown in the accompanying drawing, wherein for the purpose of illustration is shown a preferred embodiment of my invention and wherein:—

Figure 1 is a plan view of game apparatus 25 constructed in accordance with my invention, the apparatus being indicated with the projectile about to engage one of the vanes of the rotary element;

Figure 2 is a vertical sectional view 30 through the projection apparatus;

Figure 3 is a section on the line 3—3 of Figure 1;

Figure 4 is a side elevation of the index.

Referring now more particularly to the 35 drawing, the numeral 10 indicates a suitable base from which is rotatably supported a disk 11. This disk is subdivided by lines 12 radiating from its axis into the value zones 13, each bearing an indication of its value and preferably a name as Rabbit 50, Fox 100, etc. The base has a stationary index 14 coacting with the disk for identifying 40 the scoring value zone.

Supported from the base is a projectile 45 tube 15 directed to issue a projectile 16 substantially tangential to the disk. The disk upon its periphery has vanes 17, which when aligned with an index 18 carried by the base, are positioned in the path of the issued 50 projectile to be engaged thereby and by the impulse thus received cause the disk to rotate. The vanes 17 may conveniently be formed by providing projecting tabs upon the periphery of the disk which are bent

to form the vanes. The ejecting means for 55 the projectile comprises a plunger 19 operating in the tube, a spring 20 for actuating the plunger, and means for withdrawing the plunger against the action of this spring. In the present instance, the means for withdrawing the plunger comprises a lever 21, one arm of which is constructed in the form of a leg of a mule and a second lever 22, one arm of which is in the form of the head of the mule. These levers are pivoted within 60 a body structure 23 rigidly secured to the base, as at 24, and have the remaining arms thereof overlapped within the body structure, as indicated at 25. The spring 20 hereinbefore referred to is connected to the 65 second arm of the lever 21 and to a stationary part of the body 23, which preferably forms the front leg structure of the body and has its upper end so positioned as to constitute a stop limiting movement of the 70 lever 22 so that the head is normally properly positioned.

It will be obvious that when the head forming lever is depressed, the leg forming arm of the lever 21 will be moved outwardly 75 from the adjacent end of the projectile tube and at the same time, the spring 20 will be tensioned. Upon the release of the head, the leg structure will force the plunger 19 rapidly into the projectile tube, causing the projectile 16 to issue and engage one of the vanes 17. Obviously, by regulating the tension 80 under which the lever 21 is placed, the force with which the projectile 16 engages the vane may be regulated and the extent of 85 rotation of the disk determined, so that considerable skill may be developed in playing the game. The players may operate the device in turn and the player making the highest score wins.

Since the construction hereinbefore set forth is capable of a certain range of change and modification without materially departing from the spirit of the invention, I do not limit myself to such specific structure except 90 as hereinafter claimed.

I claim:—

1. In game apparatus, a base, a disk rotatably supported thereby and subdivided into value zones, a stationary index coacting with the disk for identifying the winning value zone, means for rotating said disk comprising vanes carried by the disk, means carried 100

by the base for issuing a projectile along a fixed path in which said vanes may be disposed, and means controlling the projectile issuing means operable to vary the speed 5 at which the projectile is issued.

2. In game apparatus, a base, a disk rotatably supported thereby and subdivided into value zones, a stationary index coacting with the disk for identifying the winning value 10 zone, means for rotating said disk comprising vanes carried by the disk, means carried by the base for issuing a projectile close to the disk and along a fixed path in which said vanes may be disposed, means upon the 15 base for indicating the position in which the disk must be disposed to provide engagement of a given vane by the issued projectile, and means controlling the projectile issuing means operable to vary the speed at 20 which the projectile is issued including relatively fixed and movable parts comparison of the positions of which provides an indica-

tion of the speed at which the projectile will be issued.

3. In game apparatus, as a subcombination, a projectile issuing means comprising a tube for the reception of the projectile, a plunger to engage the projectile and cause it to issue from the tube and operating mechanism for the plunger comprising a support in the form of the body and forelegs of an animal, a bell-crank lever in the form of the rear legs of the animal and having one arm thereof connected with the plunger, a second bell crank lever one arm of which 35 is in the form of the head of the animal, the remaining arms of said bell crank levers engaging and a spring coacting with said bell crank levers to resist withdrawal of the plunger from the tube. 40

In testimony whereof I hereunto affix my signature.

JEAN-BAPTISTE BOUCHARD.
